H. A. Seymour

UNITED STATES PATENT OFFICE.

ROBERT STEWART, OF LOUISVILLE, KENTUCKY.

BOILER-FURNACE.

SPECIFICATION forming part of Letters Patent No. 364,382, dated June 7, 1887.

Application filed April 13, 1887. Serial No. 234,945. (No model.)

To all whom it may concern:

Be it known that I, ROBERT STEWART, of Louisville, in the county of Jefferson and State of Kentucky, have invented certain new and 5 useful Improvements in Methods of Constructing Boiler-Furnaces; and I do hereby declare the following to be a full, clear, and exact description of the invention, such as will enable others skilled in the art to which it appertains 10 to make and use the same.

My invention relates to an improved method of constructing a boiler-furnace, and more particularly to an improvement in furnaces for return-flue boilers.

15 Heretofore boilers with tubular flues extending longitudinally from one head to the other to return the heated products of fuel combustion from the rear end of the boiler to the front end, and thence up the chimney or stack, have 20 been provided with masonry walls of brick or stone, that inclosed a flue or passage extending from the bridge-wall or back wall of the fire-chamber to the rear of the boiler. Generally, this flue has been made of considerable 25 depth and intersected a chamber at the rear of the boiler, said flue being of greater dimensions than the combined area of the flues in the boiler.

The object of my present invention is to construct 30 the furnace-walls of the boiler and so proportion them that the hot products of fuel combustion will be made to more closely envelop the lower portion of the boiler at its rear end and rear sheet of the same, so as to 35 more completely utilize the heat developed by fuel combustion and effect economy in consumption of the same.

With this object in view my invention consists in certain features of construction and 40 combinations of parts, that will be hereinafter described, and pointed out in the claims.

Referring to the drawings, making a part of this specification, Figure 1 is a side elevation in section through the longitudinal center of the 45 boiler, showing the interior construction of the furnace-walls. Fig. 2 is a rear end elevation of the boiler and its furnace-walls, showing the relative position of parts of this furnace.

A represents a cylindrical boiler for steam-generation. It is furnished with several longitudinal flues, H H, &c., that are affixed to the

flue-sheets G G' in any proper manner. The boiler A is adapted, by reason of its flues, to be set or supported in place, preferably horizontal, and surrounded by a brick-masonry 55 wall. B is the fire-chamber, having the usual grate-bars provided. At the rear of the fire-chamber a wall, C, of proper height is constructed. The bridge-wall C is preferably made concentric on its top surface to the adjacent cylindrical surface of the boiler A, to afford a semi-annular throat through which the products of fuel combustion in the fire-chamber B will pass toward the rear of the boiler. 6c

The space D below the boiler, through which the draft of the chimney draws the flame from the fire-chamber B, may be made lower than the bridge-wall C, to allow room for the ashes that incidentally accumulate, and thus assure 7c the free passage of heat-currents from the fire-chamber rearward.

At a point nearly in line with the vertical face of the rear flue-sheet, G, the rear bridge-wall, E, is erected. This wall is made with a 75 curved upper surface, and is extended upwardly around the boiler to a considerable height, thus producing an annular throat or draft-port, E', that conforms to the surface of the boiler; and in regard to the space that is 8c allowed to intervene between the surface of this curved wall E it is important to insure efficiency of operation, that the area for draft afforded by this curved port or annular passage E' be somewhat less, superficially considered, than the area of the several flues of the boiler.

At the rear of the boiler, directly opposite the flue-sheet G and at such a distance from it as to provide a proper flue or passage for 9c heat-currents that pass through the curved port E', a vertical wall, I, is erected parallel to the surface of the flue-sheet G.

The masonry walls of the furnace are made to envelop the boiler and thus retain the heat, 95 and a proper provision is made at the front end of the boiler to accommodate a vertical chimney, into which the products of combustion pass when drawn through the flues H H.

In operation, the flame from the fire-chamber B passes over the bridge-wall C, through the space D, over the rear bridge-wall, E,

thence upwardly to enter the flues G, thence forward to enter the chimney at the front end of the boiler.

The provision of the close wall I and diminished area of the port E', as compared to the joint area of the flues H, will cause the flame and heat-currents to envelop the lower and side surface of the boiler from end to end, and also be reflected upon the rear flue-sheet 10 from the wall I, so that the heat developed by fuel combustion is caused to have a more extended contact with the surface of the boiler, the result of which is, that more rapid evaporation of water and evolution of steam is effected and a consequent economy in average consumption of fuel is obtained.

Having fully described my invention, what I claim as new, and desire to secure by Letters Patent, is—

20 1. In a furnace for a horizontal return-flue boiler, the combination, with a boiler having longitudinal flues, and located in furnace-walls to receive heat from a fire-chamber below it, of a front bridge-wall, a rear bridge-wall, the rear wall by its relative position in 25 regard to the surface of the boiler affording a curved draft-port of less area than the joined area of the flues, and an ash or cinder space

or chamber located between the bridge-walls, the bottom or floor of said space or chamber 30 being below the upper surfaces of the bridge-walls, substantially as set forth.

2. In a furnace for a horizontal return-flue boiler, the combination, with a boiler having longitudinal flues secured to flue-sheets, the 35 boiler located in an enveloping wall to receive heat from a fire-chamber located below the boiler, and provided with a bridge-wall at its rear end, of a bridge-wall placed near the rear end of the boiler, and constructed to produce a curved 40 throat or draft-port, the area of which is less than the area of the flues taken together, a vertical wall to deflect heat against the rear flue-sheet of the boiler, and an ash or cinder space 45 or chamber located between the bridge-walls, the bottom or floor of said space or chamber being below the upper surfaces of the bridge-walls, substantially as set forth.

In testimony whereof I have signed this specification in the presence of two subscribing 50 witnesses.

ROBERT STEWART.
